United States Patent

Des. 239,900
Patented May 18, 1976

239,900

CHAIR

Stapleton Long, Morristown, Tenn., assignor to The Berkline Corporation, Morristown, Tenn.

Filed Dec. 19, 1974, Ser. No. 534,179

Term of patent 3½ years

Int. Cl. D6—01

U.S. Cl. D6—71

FIG. 1

FIG. 2

FIG. 1 is a front perspective view of a chair showing the invention; and

FIG. 2 is a side perspective view thereof.

The side not shown is a mirror image of that shown, and the chair back is plain and conventional.

I claim:

The ornamental design for a chair, as shown.
